THERMIONIC APPARATUS

Filed July 19, 1927

Inventor:
August Schmidt, Jr.,
by *August Schmidt, Jr.*
His Attorney.

UNITED STATES PATENT OFFICE.

AUGUST SCHMIDT, JR., OF SCHENECTADY, NEW YORK, ASSIGNOR TO GENERAL ELECTRIC COMPANY, A CORPORATION OF NEW YORK.

THERMIONIC APPARATUS.

Application filed July 19, 1927. Serial No. 206,954.

My invention relates to thermionic apparatus provided with a cathode heating element and with exciting electrodes arranged to maintain the excitation of the apparatus when it is not loaded, and has for its principal object the provision of an improved apparatus and method of operation whereby the initial current of the heating element is kept within safe limits and the excitation of the apparatus is readily established.

Various types of thermionic apparatus comprising a cathode which includes an activating material, such as barium oxide or the like, and provided with a heating element have been provided in the past. In the operation of many of these apparatus, difficulty is encountered due to the fact that the cathode heating element tends to take a comparatively large current at starting when it is cold and due to the further fact that the potential required to start ionization between the cathode and exciting electrodes is much larger than the potential required to maintain this ionization. In accordance with my invention, these difficulties are avoided by the provision of an impedance device which is so interconnected with the exciting and heating circuits of the apparatus as to limit the initial current of the heating element and cause a comparatively high voltage to be applied to the exciting electrodes when they are first energized.

My invention will be better understood from the following description when considered in connection with the accompanying drawing and its scope will be pointed out in the appended claims.

The drawing is a wiring diagram of an alternating current rectifying system wherein my invention has been embodied.

This system comprises an alternating current circuit 1 and a direct current circuit 2 which are interconnected through a transformer 3 and a thermionic device 4 provided with a heating element 5, a tubular cathode 6, anodes 7 and exciting electrodes 8.

The container of the device 4 is preferably freed from moisture, is evacuated to the degree required for the production of a substantially pure electron discharge therein, and is then supplied with a suitable gas at a pressure below that at which the discharge becomes arc-like and tends to concentrate or become localized on the cathode. For example, mercury vapor, a rare gas such as

argon or neon or a mixture of rare gases may be utilized as the ionizable medium. As previously indicated, the cathode 6 may be coated with a material having a higher electron emissivity than the cathode metal. Among the activating materials which may be utilized are barium oxide, other alkaline earth oxides, or rare earth metals such as cerium.

The transformer 3 comprises a secondary winding 9 provided with end terminals which are connected to the anodes 7 and with an intermediate terminal which is connected to the negative terminal of the direct current circuit 2. The positive terminal of the circuit 2 is connected to the cathode 6.

Current is supplied to the cathode heating element 5 and to the exciting electrodes 8 through an impedance device shown as a high reactance transformer 10 which is provided with a three-legged core 11, a primary winding 12, a secondary winding 13 connected to the heating element 5, and a secondary winding 14 connected between the heating element 5 and the exciting electrodes.

With these connections, the magnitude of the current supplied to the heating element 5 before it has become heated is limited to a comparatively low value due to the fact that the reactive drop of the winding 13 causes a comparatively large part of the core flux to be shunted through the middle leg. A comparatively high voltage is thus applied to the exciting electrodes 8 due to the flux shunted through the coil 14 when the heating element is cold and the heating current tends to be highest. The heating current is thus maintained within safe limits at starting and the exciting electrodes are subjected to a comparatively high voltage which ensures that ionization is established between the cathode 6 and the exciting electrodes 8.

As the heating element comes up to its normal operating temperature, its current decreases and the potential of the exciting electrodes 8 is decreased due to the resulting decrease in the flux of the coil 14.

With the connections illustrated, the exciting current of the device 4 is dependent on the electron emissivity of the heating element 5. It will be apparent that the intermediate terminal of the winding 14 may be connected to the cathode 6 instead of to the intermediate terminal of the secondary winding 13, so that the electron emissivity of the cathode is uti-

lized for producing the exciting current. As indicated by the dotted lines at the bottom of the middle leg of the transformer core, this leg may be provided with an air gap for ensuring that the reactance of the transformer 10 is sufficiently high.

The embodiment of the invention illustrated and described herein has been selected for the purpose of clearly setting forth the 10 principles involved. It will be apparent, however, that the invention is susceptible of being modified to meet the different conditions encountered in its use and I therefore aim to cover by the appended claims all modifications within the true spirit and scope of my invention.

What I claim as new and desire to secure by Letters Patent of the United States is:

1. The combination of an impedance device comprising a core and a plurality of windings wound upon said core, and a thermionic apparatus provided with a cathode heating element connected to one of said windings and with an exciting electrode connected to said heating element through means comprising said winding and another of said windings.
2. The combination of an impedance device comprising a core and a plurality of windings each wound on a different leg of said core, and a thermionic apparatus provided with a cathode heating element and with an exciting electrode arranged to be subjected to a voltage applied through another of said windings.

3. The combination of a transformer comprising a core and a plurality of secondary windings connected to one another at points intermediate their ends, and a thermionic apparatus provided with a cathode heating element connected between the ends of one of said windings and with exciting electrodes connected between the ends of another of said windings.

4. The combination of an impedance device comprising a core and a plurality of windings wound on different legs of said core and interconnected at points intermediate their ends, and a thermionic device comprising a cathode, a heating element mounted in proximity to said cathode and connected between the ends of one of said windings, and a pair of exciting electrodes connected between the ends of another of said windings.

5. The combination of a thermionic apparatus including a cathode heating element and an exciting electrode, and means including an impedance device for applying to said electrode a potential which is dependent on the current of said heating element.

6. The combination of a thermionic apparatus including a cathode heating element and an exciting electrode, and means connected between said heating element and said exciting electrode for limiting the starting current of said element.

In witness whereof, I have hereunto set my hand this 18th day of July, 1927.

AUGUST SCHMIDT, JR.
